Evaluation Report of Design Patent, issued by State Intellectual Property Office of the People's Republic of China for Chinese Design Patent Registration No. ZL201430040931.5, on Dec. 16, 2014, no translation Feb. 9, 2015.

Primary Examiner — Paula Greene(57) **CLAIM**

The ornamental design for a communications headset, as shown and described.

DESCRIPTION

FIG. 1 is a perspective view of a communications headset showing my new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines showing the unclaimed features form no part of the claimed design.

1 Claim, 3 Drawing Sheets---
